UNITED STATES PATENT OFFICE.

GODFREY ENGEL, JR., OF BROOKLYN, NEW YORK, ASSIGNOR TO MCGANN MANUFACTURING COMPANY, INC., OF YORK, PENNSYLVANIA, A CORPORATION OF PENNSYLVANIA.

DRYING APPARATUS.

Application filed January 12, 1924. Serial No. 685,805.

To all whom it may concern:

Be it known that I, GODFREY ENGEL, Junior, a citizen of the United States, and a resident of Brooklyn, in the county of Kings 5 and State of New York, have invented certain new and useful Improvements in Drying Apparatus, of which the following is a specification.

The invention relates to apparatus for 10 drying various substances or products and particularly to apparatus capable of efficiently evaporating liquid from such material as ore or ore concentrates.

One object of the invention is to produce 15 a dryer capable of economic operation and of high efficiency, and a further object of the invention is to provide a dryer of such form and design as to afford a large capacity while occupying very small floor space.

20 A further purpose of the invention is to provide a dryer which may be readily constructed and installed at minimum expense, and one in which the parts are so constructed and combined as to permit ready accessibility to the interior of the apparatus and to facilitate repairs or renewal of parts when required.

The invention and satisfactory means for carrying the same into effect will be fully 30 understood from the detailed description hereinafter presented, reference being had to the accompanying drawings, in which:

Fig. 1 is a plan view of the dryer of my invention and illustrates the direct connection of the same with the furnace;

Fig. 2 is a central vertical section through the same taken on the dotted line 2—2 of Fig. 1;

Fig. 3 is a transverse sectional plan view taken on the dotted line 3—3 of Fig. 2;

Fig. 4 is a transverse sectional plan view taken on the dotted line 4—4 of Fig. 2;

Fig. 5 is a similar view taken on the dotted line 5—5 of Fig. 2;

Fig. 6 is a vertical section, on a larger scale, through a portion of the apparatus and taken on the dotted line 6—6 of Fig. 3;

Fig. 7 presents a detail plan and side view, 50 on a larger scale, illustrating radially disposed matching clamping members which are adapted to receive the inner ends of the radial scraper or pusher bars and by which

said bars are connected with the center rotary shaft;

Fig. 8 is an end view of a feed or discharge nozzle containing a rotary sealing member I will make use of at both nozzles when the apparatus is operated under a vacuum;

Fig. 9 is a vertical section through the same taken on the dotted line 9—9 of Fig. 8, and

Fig. 10 is a central vertical section through a slightly modified form of the dryer.

The apparatus of my invention is vertical and cylindrical and mounted on legs or supports 10, and hence the apparatus occupies the minimum of floor space.

The main casing of the dryer may be made 70 of either metal or wood and is formed of an outer shell 11, an inner shell 12, a top or cover 13 and a bottom 14.

The outer and inner shells 11, 12 are 75 spaced apart by an upper continuous ring 15 and lower spacing blocks or pieces 16 to form between said shells a cylindrical chamber 17 for the heating medium, which will pass from the furnace 18 through piping or flues 19 to nozzles 20 secured to the outer shell 11 and communicating with the upper end of the chamber 17, and the lower end of said chamber is in communication with the main interior chamber of the apparatus through the large spaces left 80 between the spacing blocks 16 (Fig. 4).

The upper end of the inner shell 12 extends above the upper end of the outer shell 11 and also above the spacing and sealing ring 15, and said end of the inner shell is 90 reinforced by an angle ring or band 21 secured thereto and affording a lateral flange to which the peripheral portions of the top or cover 13 are detachably secured.

The top or cover 13 is domed upwardly 95 and has an inlet nozzle 22 for the material to be treated, an exhaust nozzle 23 for the vapor arising from the material treated, a central ball-bearing cap 24 for the upper end of the vertical shaft 25 and a man-hole and cover 26.

The bottom 14 is dished upwardly and at its edges has a downwardly projecting annular flange 27 which is secured to and within the lower edge portions of the outer shell 11, and said bottom 14 has an outlet 100

or discharge nozzle 28 for the material treated and a center ball-bearing 29 for the lower end of the vertical shaft 25.

The outer shell 11 extends considerably below the inner shell 12 (Fig. 2) whose lower edge terminates at the lower edges of the spacing blocks 16, the lower or discharge end of the main chamber of the dryer being enlarged by this construction.

10 The lower end of the outer shell 11 is strengthened by a continuous reinforcing angle 30 secured thereto and whose laterally extending flange bears upon and is secured to the upper ends of the supporting legs 10.

15 The vertical shaft 25 is supported in the bearings 24, 29 and has secured to its lower end a suitable driving gear 31 through which power may be applied to said shaft from any convenient source for rotating the same and the features connected therewith.

20 Within the main chamber of the dryer I provide a plurality of horizontally disposed plates or disks 32 alternating with horizontally disposed plates or disks 33, the plates 32 each affording a flooring which inclines downwardly and outwardly from the center shaft 25, and the plates 33 each affording a flooring which inclines downwardly and inwardly toward said shaft, said plates 32 being domed upwardly into low conical shape and the plates 33 being dished downwardly into low inverted conical shape. The plates 32, 33, are stationary and supported from the side walls of the inner shell 12 by means of brackets 34 secured to said walls and bars 35 extending radially below said plates from said brackets. The plates 32 are less in diameter than the shell 12 and along the peripheral edges of said plates is left an annular space down through which the material under treatment may descend to the respective plates 33. The plates 33 extend out to the inner wall of the shell 12 and are open at their center around the shaft 25, as denoted at 36 (Fig. 4), and the material under treatment is caused to descend through the open centers 36 and fall on the plates below them, the material thus taking a serpentine course through the apparatus.

25 The material which falls from the lowermost plate 33 descends upon the bottom 14 and is thence swept or moved to the outlet or discharge nozzle 28, as hereinafter explained. The plates 32, 33 may be either solid or perforated or of screen type, as may be preferred and as indicated in Figs. 2 and 10 respectively.

30 Upon and arranged to travel over the plates 32 and to move the material under treatment that may be thereon over the outer edges of said plates, are a series of angularly disposed pushers or scrapers 37, and upon and arranged to travel over the plates 33 and to move the material that may

be thereon over the inner edges of said plates and into the openings 36, are a series of angularly disposed pushers or scrapers 38 (Fig. 4), which correspond with the scrapers 37 but are disposed at a different angle therefrom, the scrapers 37 being arranged to sweep or push the material outwardly over the plates 32, and the scrapers 38 being disposed to sweep or push the material inwardly over the plates 33. The scrapers 37, 38 are in the form of blades having lower edges matching the surfaces of the respective plates 32, 33 and upper edge flanges 39 (Fig. 6) which are secured to segmental plates 40 by means of bolts 41 which pass through holes in said flanges and through segmental slots 42 in said plates 40, said bolts and slots permitting the scrapers to be angularly adjusted in accordance with the nature and condition of the material under treatment and the timing desired for moving the material off from said plates. The segmental plates 40 are rigidly secured to the base of inverted T-iron bars 43, and the vertical flanges of these bars 43 are securely bolted between radial clamping members 44 (Fig. 7) rigidly pinned or otherwise secured onto the shaft 25. The scrapers 37, 38 are by the means just described, connected with the vertical shaft 25, and during the rotation of said shaft said scrapers are caused to sweep over the upper surfaces of the plates 37, 38 and scrape or push the material off from the same.

35 The material which falls on the bottom 14 from the lowermost plate 33 is acted on by scrapers 45 whose lower edges are concaved to match the convexity of the bottom 14 and which scrapers are fastened to segments 46 secured to radial bars 47 carried by clamping members 48 secured to the shaft 25, said segments 46, bars 47 and clamping members 48, corresponding with the like parts 40, 43, 44 hereinbefore described. The scrapers 45 are by means of the segments 46 adjusted to match the convexity of the bottom 14 and angularly set to direct the material from said bottom to the discharge nozzle 28.

40 The inlet or feed nozzle 22 and the outlet or discharge nozzle 28, may be plain open nozzles, as shown in Fig. 2, but when occasion renders it desirable, as when drying under a vacuum, I will provide inlet and outlet nozzles of the form shown at 49 in Figs. 8 and 9, these nozzles having arcuate sides and enclosing rotary winged gates 50 mounted on shafts 51 to which power may be applied through a belt wheel 52. The gates 50 are adapted to feed the material into and from the dryer, while at the same time effecting a closure against the arcuate sides of the nozzle, in a well-understood manner.

In the employment of the apparatus, the product to be dried or evaporated is fed in suitable and continuous volume through the inlet nozzle 22 and at first falls upon the 5 top plate 32 and is by means of the scrapers 37 thereat moved along upon and to the edges of said plate and thence falls upon the first plate 33 below said top plate 32 and is moved along upon and to the central 10 opening 36 of said plate 33 by the scrapers 38 moving over the surface of said plate. Upon the material reaching said opening 36 of the aforesaid plate 33 it becomes unsupported and falls upon the next lower plate 15 32, over which the material is moved by the scrapers thereon until it falls over the outer edges thereof and reaches the next lower plate 33, upon which the material is moved 20 by the scrapers thereon until it reaches and is pushed over the edges of the central opening in said plate 33, whence the material falls upon the convex bottom 14 and is thereon acted upon by the scrapers 45 and by them moved to the exit or discharge nozzle 28 and passes to a suitable receiver or conveyor, not shown. The scrapers have a 25 comparatively slow movement imparted to them from the central shaft 25 and the material under treatment is by said scrapers 30 very thoroughly agitated and distributed over the plates 32, 33 and is repeatedly turned over to expose all its particles to the drying medium. The apparatus of my invention may be equipped with as many of 35 the alternating plates 32, 33 as may be found to be desirable.

The heating medium, air or gas, produced by the furnace 18, flows through the conduits and enters the upper portion of the 40 chamber 17 surrounding the inner shell 12 or the retort proper, and while heating said shell throughout, descends through said chamber 17 and passes from the lower end of the same into the lower end of the drying chamber, whence the heating medium ascends on a zig-zag course through the central openings of the plates 33 and around the peripheral edges of the plates 32 and finally leaves through the exhaust 23, which 45 will usually be connected with a pump, blower, stack or the like to induce a steady current through the apparatus. The heating medium while traveling upwardly through the drying chamber, is compelled 50 also to travel laterally between the plates 32, 33 and against the material thereon and also through the material descending from one plate to another in series, with the result that all particles of the material are 55 exposed to the action of the heating medium, which absorbs and carries off the moisture from said material. It is to be noted that in the operation of the apparatus the heating medium moves in an opposite direction to that of the material under treat- 60

ment, thereby increasing the efficiency of the apparatus.

In the operation hereinbefore described, the heating medium passes into direct contact with the material under treatment but 70 there are many substances requiring evaporation which cannot be exposed to the direct action of the heating medium, and in instances of this kind a sealing ring 70, Fig. 10, corresponding to the ring 15, will be 75 used at the lower end of the chamber 17 in lieu of the blocks 16, thereby sealing the chamber 17 from direct communication with the drying chamber of the apparatus, the apparatus then being used as a vacuum 80 dryer and the material being subjected to a lower temperature. It will also be found to be convenient and sometimes very desirable, to introduce heating coils, as at 71, Fig. 10, between the plates 32, 33 and connect them with the chamber 17, thus even in vacuum drying providing for an increased temperature in the drying chamber 85 of the apparatus.

In the event of sealing the lower end of 90 the chamber 17 in the manner described, said chamber at its lower end should be provided with a drain 72 for the escape of water of condensation from said chamber.

I have hereinbefore referred to air and 95 gas as the heating medium, but when the apparatus is made use of as a vacuum dryer, the heating medium may also be steam or hot water.

What I claim as my invention and desire 100 to secure by Letters Patent, is:

1. A vertical drying apparatus comprising an outer cylindrical shell, an inner cylindrical shell spaced from the outer shell to form between the two shells a chamber 105 for a heating medium to be supplied thereto, a cover having an inlet for the material to be dried, a bottom having an outlet for the material treated, and interior mechanism comprising two series of alternating stationary disks supported from the inner walls of the apparatus to one after another receive the material fed to the apparatus, the disks of one series being less in diameter 110 than the chamber of the apparatus to permit the discharge of the material over the peripheral edges thereof to the disks of the other series, and the disks of said other series being extended outwardly to the inner wall of the drying chamber to receive said 115 material and having open centers to permit the discharge of the material therethrough to the disks of smaller diameter, a central vertical shaft extending through the apparatus, a series of radial arms secured to said 120 shaft and extending over said disks respectively, and a series of scraper blades secured to said arms and engaging the floors of said disks, the blades engaging the disks of smaller diameter being adapted to move 125 130

the material over the peripheral edges thereof, and the blades engaging the other disks being adapted to discharge the material through the central openings therein.

5 2. Drying apparatus as claimed in claim 1, in which the outer shell extends below the inner shell and in which said bottom is upwardly domed and receives the dried material from the lowermost disk, and in 10 10 which scraper blades are secured to said shaft to move over the convex surface of said bottom and move the material to said outlet therefor.

3. Drying apparatus as claimed in claim 15 1, in which the inner shell extends above the outer shell and has an angle-iron reinforcing band secured around its upper edge receiving the peripheral edges of the cover, and in which the outer shell extends 20 below the inner shell and has an angle-iron band secured thereto affording means by which the apparatus may be supported on legs or the like.

4. Drying apparatus as claimed in claim 25 1, in which the disks of smaller diameter are of shallow cone-shape and the disks of larger diameter are of inverted shallow cone-shape, and in which said disks are supported by radial bars extending to substantially the middle of said disks and secured at their outer ends to brackets fastened to the inner wall of the inner shell.

5. Drying apparatus as claimed in claim 35 1, in which the chamber for the heating medium is sealed at the upper end and open at its lower end below the series of disks, and in which the exhaust for vapor and gas is at the upper end of the apparatus, whereby the heating medium is caused to take a 40 circuitous course upwardly against the particles of the material agitated on and falling from the disks.

6. Drying apparatus as claimed in claim 45 1, in which the chamber for the heating medium is closed at its upper end by a ring interposed between said shells, and in which said shells at the lower end of said chamber are spaced apart by means permitting the heating medium to freely pass from said 50 chamber into the drying chamber below said disks, and in which the exhaust for vapor and gas is at the upper end of the apparatus.

7. Drying apparatus as claimed in claim 55 1, including conduits leading from a furnace or other source of supply for the heating medium, into opposite sides of the upper end of said chamber formed between said shells, and in which said chamber is open 60 at its lower end below said disks.

8. Drying apparatus as claimed in claim 1, in which the cover has a nozzle at its said

inlet for directing the material toward the center of the top disk, an exhaust for vapor and gas and a manhole.

9. Drying apparatus as claimed in claim 1, in which said radial arms have segments to which said blades are secured by means permitting of their angular adjustment.

10. Drying apparatus as claimed in claim 70 1, in which said radial arms have slotted segments to which said blades are secured by bolts adjustable along said slots to permit angular adjustment of the blades.

11. Drying apparatus comprising a vertical drying chamber having an inlet at its upper end for the material to be dried and an outlet at its lower end for the material treated, two series of alternating disks to one after another receive the material on its 80 passage through the apparatus, the disks of one series permitting the discharge of the material over their peripheral edges to fall upon the disks of the other series, and the disks of said other series having open centers to permit the discharge of the material therethrough to fall upon the central portions of the disks of the first series, a central vertical shaft extending through the apparatus, a series of radial arms connected 90 with said shaft and extending over said disks and having a plurality of segments, and scraper blades secured to said segments and engaging the floors of said disks for moving said material along over and off 95 from the same, the means securing the blades to said segments permitting angular adjustment of the blades.

12. Drying apparatus as claimed in claim 11, in which said segments contain arcuate 100 slots and in which said blades are adjustably secured to said segments by bolts engaging the blades and extending through said slots.

13. Drying apparatus as claimed in claim 11, in which said radial arms are of inverted 105 T-shape and carry arcuate slotted segments secured to the base flange thereof, and in which said blades are flanged at their upper edges and adjustably secured to said segments by bolts engaging the flanges of the 110 blades and extending through the slots of said segments.

14. Drying apparatus as claimed in claim 11, in which said radial arms are of inverted T-shape, and in which the means connecting 115 said arms with the central shaft comprises matching members encompassing and fastened to the shaft and having radial arms between which the webs of said inverted T-bars are secured.

Signed at New York city, in the county of New York and State of New York, this 11th day of January, A. D. 1924.

GODFREY ENGEL, JUNIOR.
